UNITED STATES PATENT OFFICE.

ANDREW J. CONNELL, OF NEW YORK, N. Y., ASSIGNOR TO SUPERIOR STEEL DOOR AND TRIM CO., INC., OF COLLEGE POINT, NEW YORK, A CORPORATION OF NEW YORK.

METAL DOOR JAMB.

Application filed July 21, 1921. Serial No. 486,383.

To all whom it may concern:

Be it known that I, ANDREW J. CONNELL, a citizen of the United States, residing at College Point, county of Queens, city and 5 State of New York, have invented new and useful Improvements in Metal Door Jambs, of which the following is a specification.

This invention relates to metal door-jambs and more particularly to jambs comprising 10 fixed bucks arranged to cooperate with removable door-stops.

In the construction of metal door-jambs it has hitherto been usual to provide bucks having door-stops permanently connected 15 or integral therewith. These door-stops were designed for use with doors having a particular hinge and latch arrangement, and when such stops had once been machined to accommodate the hinges and striking 20 plate of a particular type of door, no other door could be employed. Moreover, it is customary to secure door-bucks permanently 25 in place during the erection of the walls of a building. Therefore, it has been necessary to completely design the metal doors in advance of construction of the building, often resulting in unnecessary delay. When as sometimes occurs the bucks were set inaccurately, so as to be a little too close together or too far apart, then the previously 30 designed doors would not fit properly in their doorways, and it was necessary to construct new doors. The bucks once set in place would accommodate only one type of 35 door, opening in a predetermined direction. If through any change of plans it became desirable to employ a different type of door, or to have the door swing open in the opposite direction, it was necessary to replace 40 the entire buck, to do which required the demolition of the masonry to which the buck was attached, a difficult and expensive operation.

It is the principal object of this invention 45 to provide an improved metal door-jamb comprising a buck arranged to be permanently fixed to the masonry as before, and separate door-stops which may be quickly attached to or removed from the bucks. By 50 the use of separate stops a standard form of buck may be set in place during the erection of the walls of a building, while the doors need not be designed until time for finishing the building. Moreover, by the use of separate stops the door may be hung to open 55

in either direction, as desired at the time of hanging, or if it later becomes necessary to reverse the direction of the door swing, this can readily be accomplished by removing the stops from the bucks and interchanging them. Should the bucks be inaccurately positioned in the building, after the construction of the doors, it is merely necessary to provide new stops to properly accommodate the doors to the actual location of the bucks.

For the purpose of rendering the invention readily understandable, one preferred embodiment has been illustrated in the accompanying drawings in which:

Fig. 1 is a horizontal section of a doorway showing a door-jamb arranged in accordance with this invention;

Fig. 2 is a perspective face view of a door-stop;

Fig. 3 is a perspective rear view of the stop shown in Fig. 2; and

Fig. 4 is a perspective of a detail.

In these drawings there are shown two quoins 1 of a doorway to which are secured vertically positioned door-bucks 2 and 3. As shown, the door-bucks and molding or trim may be made of a single piece of sheet-metal having in-turned margins 4 resting against the plastering, and having face portions 5 to which door-stops may be secured. As shown, the two face portions 5 are separated by a stop-bead or door-abutment 5^a, which is preferably formed integrally and centrally between the side edges of the buck. 90 The opposite sides 5^b of the stop-bead or door-abutment 5^a are, as illustrated, rectilinear in outline so as to enable seats of similar conformation to be formed on opposite sides of said bead. The bucks may 95 be seated in place during the erection of the masonry as usual, and may be permanently secured by any well known means such as the usual reinforcing plates 21. A horizontal member 25 of the door-frame, 100 such as a lintel or sill is also shown.

In order to accommodate the bucks to any desired door, there are provided removable door-stops 6, 7, 8 and 9 which may be designed at any time during construction or after its completion to cooperate with any particular door. As shown, these door-stops most desirably are made up of channel-shaped strips of sheet-metal comprising body portions 15 and marginal portions 11, 110

and are cut-away as at 22 to accommodate the hinges or striking plates. The door-stops may be secured to the buck in any suitable manner which allows their easy removal, but there is most desirably provided a small upwardly extending tongue 10 which fits into a suitably positioned slot in the lintel (Fig. 3). The weight of the door when hung from the stop will then tend to force the marginal portions 11 of the stop tightly against the face portion 5 of the buck. For the double purpose of more firmly securing the door-stop to the buck and providing a support for the hardware such as hinges or striking-plates there are provided plates 12, shaped as shown in Fig. 4. Each plate 12 comprises flat end portions 13 and a depressed central portion 14. As seen in Figs. 2 and 3 the end portions 13 of plates 12 when in place register with the margins 22 of the body portion 15 of the door stops, while the entire plate 12 fits snugly against the outer marginal portion 11 of the door-stop. The plates are permanently secured as by welding or the like, to the body portion 15 of the stop. The depressed central portion 14 of each plate 12 is drilled and countersunk in one or more places as at 16, to receive one or more securing screws 17. These portions 14 are also arranged to hold hinges 18, or striking-plates, a number of tapped holes being provided as at 19 to receive screws 20. The plates 12 are so shaped as to allow the face of the hinges 18 to set flush with the face 15 of the stops.

In hanging a door with the devices of this invention, it is merely necessary to slide the tongue 10 into its lintel-groove, insert screws 17 in their holes 16 which register with holes 24 tapped in the face of the buck, and then by tightening the screws firmly secure the hanging-stop to its buck. If desired plates 23 may be supplied to reinforce the face of the buck where the screws 17 enter.

The blank stops 8 and 9 are secured by screws 17 which engage their face portions 15 and holes 24 arranged in the respective face portions 5 of the bucks to allow any stop to be secured to either side of either buck. The stop 7 may have a suitably positioned striking plate secured thereto in the manner shown and described for securing the hinges to the stop 6, or there may be an integral striking plate.

Stops 6 arranged in this way, with the manner of their attachment to the bucks concealed by the hinges 18, and stops 7, 8 and 9 having the heads of their securing screws 17 setting flush with their face portions and painted over, present an appearance indistinguishable from the bucks equipped with integral door-stops previously in general use, while overcoming the disadvantages heretofore set forth.

In case it is found that the opposite bucks

of a doorway have been set too close together so that the door does not fit its frame, it is merely necessary to cut away the marginal portions 11 of the stops until a fit is secured. If the bucks are too far apart, the margins 70 may be built up to size, or new stops may be provided. In either of the above cases a new door would have been required with the form of buck previously employed.

While one preferred embodiment of the 75 invention has been described in detail, it is to be understood that this is merely for the sake of clearness, and not to limit the scope of the invention as defined in the appended claims.

I claim:

1. A door-jamb comprising a sheet-metal buck having integrally formed a face portion and side molding portions so as to embrace the edge and sides of the door opening; a sheet-metal door-stop arranged on the said face portion and means for detachably connecting said door stop to said face portion.

2. A door-jamb comprising a sheet-metal door-buck having two face portions and side molding portions formed integrally with said face portions, and a detachable sheet-metal door-stop arranged on one of said faces and adapted to cooperate with either of said face portions.

3. A metal door jamb embodying, in combination, a sheet-metal buck having a face provided with two separated face portions of substantially equal dimensions, and a stop bead separating said face portions and forming, at opposite sides thereof, seats of similar conformation, and a detachable sheet-metal door-stop arranged on one of said face portions and adapted to cooperate with either of said face portions.

4. A metal door jamb embodying, in combination, a sheet-metal buck having a face provided with two separated face portions of substantially equal dimensions, and a stop bead separating said face portions and having, at opposite sides, rectilinear sides forming with said face portions seats of similar conformation at such opposite sides, and a detachable sheet-metal door-stop arranged on one of said face portions and adapted to cooperate with either of said face portions.

5. A metal door jamb embodying, in combination, a sheet-metal buck having a face provided with two separated face portions of substantially equal dimensions, and a stop bead formed integrally with said face portions, separating the same and having, at opposite sides, rectilinear sides forming with said face portions seats of similar conformation at such opposite sides, and a detachable sheet-metal door-stop arranged on one of said face portions and adapted to cooperate with either of said face portions.

6. A door-stop comprising a sheet-metal

channel-member having a body portion and turned margins, cut-away portions to accommodate hardware such as hinge plates, and plates registering with said cut-away portions to support said hardware, said supporting plates being adapted to cooperate with fastening-means concealed by said hardware.

7. In a door-frame, the combination with two sheet-metal door-bucks in spaced relation each having integrally formed a face portion and side molding portions so as to embrace the edge and sides of the door opening, and detachably securable sheet-metal means for hanging a door from either buck.

8. A door-frame comprising oppositely disposed sheet-metal bucks each having integrally formed a face portion and side molding portions so as to embrace the edge and sides of the door opening, and sheet-metal door-stops adapted to cooperate with a door to close the space between the bucks, said stops being detachably secured to said bucks.

9. In a door-frame, the combination of two sheet-metal door-bucks in spaced relation each having integrally formed a face portion and side molding portions so as to embrace the edge and sides of the door opening, and separate sheet-metal means for

hanging a door to one of said bucks and filling the space remaining between the door when in closed position and the other buck.

10. In a door-frame comprising a sheet-metal buck and a lintel each having integrally formed a face portion and side molding portions so as to embrace the edge and sides of the door opening, a sheet-metal door-stop having a lintel engaging portion, and screw threaded means for detachably securing the stop to the buck.

11. In a door-frame, the combination with a sheet-metal buck comprising a face portion and side molding portions formed integrally therewith, a lintel connected with said buck and having a slot to receive door-stop securing means, the face portions of said buck having apertures to cooperate with other door-stop securing means, and means for securing a door-stop to said lintel and to said buck.

12. In a door-frame, the combination with two oppositely disposed sheet-metal bucks each comprising two face portions and each having side molding portions formed integrally therewith, a pair of door-stops adapted to cooperate with a door, a pair of blank door-stops, and means for interchangeably securing said pairs of door-stops to the face portions of said bucks.

ANDREW J. CONNELL.
